UNITED STATES PATENT OFFICE.

KENNEDY DOUGAN, OF MINNEAPOLIS, MINNESOTA.

INTERNAL-COMBUSTION ENGINE.

1,299,433.

Specification of Letters Patent.

Patented Apr. 8, 1919.

Application filed September 1, 1911, Serial No. 647,175. Renewed January 10, 1918. Serial No. 211,317.

To all whom it may concern:

Be it known that I, KENNEDY DOUGAN, a citizen of the United States, residing at Minneapolis, in the county of Hennepin and 5 State of Minnesota, have invented certain new and useful Improvements in Internal-Combustion Engines, of which the following is a specification.

My invention relates to internal combustion engines of the type shown and described in my applications, Serial Numbers 635,206, filed June 24, 1911, and 644,504, filed August 17, 1911, in which the force of the explosion within the combustion chamber operates to 10 raise a weight, the energy thereby accumulated being used to perform useful work when the weight falls. My present invention relates to an explosion engine of this type combined with a pump the piston of 15 which is connected to the weight-operating member of the engine and the invention has in view especially providing means for positively operating the different sets of exhaust and intake valves in timed relation both 20 with respect to the sets of valves in different engine units and the different valves in each engine unit.

It is the chief object of the invention to provide operating means for the exhaust 25 and intake valves of the different engine units which shall be actuated from or through the exploding charge of the active engine cylinder when the weight-operating member and pump piston is raised and which 30 shall be further actuated by the fluid within the pumping cylinder through compression thereof when the pumping piston starts to descend. It is also an object of my invention to combine with these two sets of actuating means a single actuating member for 35 both sets of valves in each engine unit, with means relatively positioned on said actuating member not only for operating the exhaust and intake valves of the given unit in 40 timed relation but for operating the exhaust and intake valves of all of the engine units in successively timed relation, so that an exhaust valve will be opened only at the time of a completed explosion in the cylinder in 45 which said valve is located, and an intake valve will be opened only when the piston begins to ascend in the engine unit next to 50 be charged in the cycle of operation of the entire engine.

55 It is also an object of my invention to provide in combination with the means herein-

before mentioned for operating the intake valves other means for automatically cutting off or closing said intake valve at a point in the upward movement of the charging piston such as will permit introduction of the desired charge within the cylinder of the engine unit to which said piston belongs. This cut-off mechanism provides means for accurately adjusting the point in said engine 60 stroke at which automatic cut-off shall take place, such adjusting means being sensitive to a high degree and comprising a feature of importance in my invention.

Another object of my invention is to provide gravity actuated circuit closing means for operating the ignition so constructed and arranged that such operation will take place at the moment of full stop of the descending 70 stroke.

Other objects and advantages of my invention will appear in the detailed description thereof and are particularly pointed out in the claims.

In the drawing, illustrating the application of my invention in one form,—

Figure 1 is a sectional elevation side view of the weight-operating member and connected parts. Fig. 2 an elevation view taken at right angles to Fig. 1 with some parts 85 omitted. Fig. 3 is a plan view of one of the engine cylinders viewed from above. Fig. 4 is a diagrammatic view showing relative position of the four valve operating cams at any given time. Fig. 5 is a detail view of 90 the cam actuating ratchet. Figs. 6 to 8, inclusive, illustrate details of the automatic intake cut-off devices.

Frame members 10 and 11 have secured thereto cylinders 13 and 14, preferably one 95 above the other, the pistons 15 and 16 of which are connected by piston rods 17 and 18 to cross bars 19 and 20 forming parts of a weight-operating yoke member 21. The yoke-operating member 21 is also provided 100 with a lower cross bar 22 which is secured to piston rod 23 of a piston 24 working in a pumping cylinder 25, said pumping cylinder being surrounded at the bottom thereof with an enlarged cylindrical casing 26 forming a 105 chamber into which the pumping cylinder opens through elongated passages 27. Upon one of the cross bars, as shown, cross bar 20, is secured a receiving tank 27. Water may be pumped into this tank or drained therefrom so as to vary the aggregate mass as may 110 be desired.

Intake valves 28 and 29 and corresponding exhaust valves 30 and 31 are provided in the bottom of cylinders 13 and 14, respectively, relatively positioned, as indicated in Fig. 3. Each of these valves comprises a bifurcated stem 32 pivotally connected at 33 to a lever 34 centrally pivoted to a bracket 35 extending from the bottom of each of said cylinders, the free end 36 of said levers being drawn upward by means of springs 37 attached to an arm 38 projecting from each of said cylinders 13 and 14, the operation of such spring through lever 34 being such as normally to hold the valves closed, the springs being strong enough to perform this function against any pressure not materially greater than atmospheric pressure. Each of the levers 34 is provided with a cam-like head 39 immediately below the pivotal point of attachment with the valve stems. Journaled in hangers 40 and 41 immediately beneath valves 29 and 31 of cylinder 14 is a shaft 42, a similar shaft 43 being journaled beneath valves 28 and 30 in hangers 44, 45 depending from the bottom of cylinder 13. Fast upon shaft 42 is a cam 46 located immediately below head 39 of lever 34 connected with exhaust valve 31, a similar cam 47 being fast on shaft 43 and operatively positioned below head 39 on lever 35 connected with exhaust valve 30. A similar cam 50 is loose on shaft 42 beneath enlarged head 39 on intake valve 29, another of such cams 51 being loose on shaft 43. Each of these cams has for the major part of its circumference a circular face 52, a single high portion 53 being provided on each cam. The relative rotative positions of the high places on the four cams, 46 and 50 on shaft 42, and 47 and 51 on shaft 43, is shown in full lines in Fig. 4, in which it will be seen that the high place 53 of each succeeding cam taken in the order of the two on shaft 42 and then the two on shaft 43 is a quarter of a revolution or ninety degrees behind the next preceding cam. If, therefore, all of the cams are simultaneously moved a quarter turn at each actuation it will take four of such movements to bring the high portion 53 of any cam from its upright or active position again to such upright and active position, during which the other cams in the order shown will each have occupied and been withdrawn from such active position, and in being so actuated have each opened and closed the valve with which it is associated, opening taking place when the portion 53 goes from the position shown at the right of Fig. 4 to its upright position and closing taking place when said high portion goes from the position shown in full lines at the left of Fig. 4 to the position of the cam next thereto on the right. As indicated, the arrangement is such that an exhaust valve and

then an intake valve are successively operated in one cylinder immediately after which an exhaust valve and then an intake valve are operated in the other cylinder. This arrangement is such that both valves are closed in the cylinder in which an explosion takes place, the exhaust valve then opening to permit cleaning of the cylinder, the intake valve of said cylinder thereafter opening to permit charging at the same time that explosion takes place in the other cylinder in which both valves will now be closed, special cut-off means later to be described closing intake valve at a predetermined point in the stroke to fix the volume of the charge. 70 75 80

Through means connected with both cylinders of the engine units the shafts 42 and 43 are simultaneously rotated a quarter turn at the moment of explosion in either cylinder; and through means connected with 85 the pumping cylinder said shafts 42 and 43 are simultaneously rotated in the same direction another quarter turn at the moment that pumping action is begun by reason of descent of the weight-operating member and 90 return engine stroke. The first of these means comprises a cylinder 54 connected by port 55 with cylinder 14 and a cylinder 56 connected by port 57 with engine cylinder 13. A piston 58 works in cylinder 56 the piston rod 59 of which is bent outwardly, as shown at 60, and bent down again, as shown at 61, to be integrally united with the piston rod 62 of piston 63 working in cylinder 54. An arm or pair of arms 65 is pivotally connected at 66 to rod 59, said arms at the other end being pivotally connected to a rocking member 67 having pivoted at 68 a pawl 69 with a weighted end 70 for holding said pawl in engagement with the teeth 71 of a four-toothed ratchet 72 fast on shaft 42. Similar arms 73 are pivoted at 74 to rod 59 and to a ratchet-operating pawl engaging a four-toothed ratchet 75 on shaft 43. It will be seen, therefore, that an explosion in either cylinder 13 or 14 will, through action of gas entering cylinder 56 or 55, cause piston 58 or piston 63 to lift rod 59 and simultaneously rotate shafts 42 and 43 a quarter turn. 100 105 110 115

A cylinder 76 communicates by means of port 77 with the bottom of pumping cylinder 25, said cylinder having therein a piston 78 to which is connected a piston rod 79, said piston rod being in turn pivoted at 80 to a pawl operating member 67 having a pawl engaging a four-toothed ratchet 81 on shaft 43. A link 82 is pivotally connected at 83 with a pawl-operating member 67 having a pawl engaging a four-toothed ratchet 84 fast on shaft 42. When therefore, the weight-operating member together with pumping piston 24 starts to descend, water under pressure will enter cylinder 76 through port 77 and, through piston 78, rod 79 and 120 125 130

link 82, will simultaneously rotate shafts 42 and 43 another quarter turn in the same direction that said parts were rotated through rod 59. It follows, therefore, that at the beginning of each upward and each downward stroke of the weight-operating members both shafts 42 and 43 are simultaneously rotated a quarter turn with the result that at each of said movements the cams 46, 47, 50 and 51 are moved so that one of said cams is caused to open a valve and the other to be positioned so that the valve may close. It is noted that after rod 59 has been lifted by an explosion said rod and the parts connected therewith are returned to initial position by means of a compression spring 85 positioned upon an arm 86 on one of the cylinders and engaged by an arm 87 of a lever pivoted intermediate its ends at 88 to a pivoted link 89, the other end 90 of said lever being pivoted at 91 to rod 59. Atmospheric pressure acting upon piston 78 will restore said piston and the parts connected therewith to initial position upon the ascent of pumping piston 24. Spring 85 will be strong enough to resist charging pressure within the engine cylinder.

With respect to the exhaust valves 30 and 31, it is noted that the operating cams therefor are so positioned that one or the other of these valves is always opened at the beginning of a down stroke and is not closed until the moment of explosion which starts an upstroke, each valve of course being operated by alternate down strokes. The cams for operating the intake valves 28 and 29 are so positioned as to open one or the other of said valves at the beginning of each upward stroke, but special cut-off mechanism is provided whereby said intake valves will be automatically closed at any point desired of the upstroke. To effect this, cams 50 and 51 are loose on shafts 42 and 43, respectively, each of said cams being provided with a pair of lugs 92 and 93 between which operates a finger 94 on a collar 95 secured to each of shafts 42 and 43. Cams 50 and 51, therefore, will be free to rotate upon shafts 42 and 43 independently of said shafts between the limits permitted by said lugs 92 and 93, although said cams will be rotated by rotation of said shafts through engagement of finger 94 with lug 92. Carried by trunnions pivotally mounted in arms 96 and 97 on pumping cylinder 25 (a similar arrangement being indicated diagrammatically as attached to engine cylinder 13 at 98) is a cylinder 99 having therein a restricted portion 100 and an enlarged portion 101, as clearly shown in Fig. 5. Within this cylinder works a piston 102 of the diameter of said restricted portion, said piston being pivotally connected by a rod 103 to cam 51 at 104, as best shown in Figs. 6 and 8, the point of connection 104 being carried away from

the end of shaft 43 by means of an off-set member 105 so that piston rod 103 has crank connection with cam 51 and as said cam is rotated the rod 103 will thereby be caused to move up and down. A spring 106 secured to the end of cylinder 99 and a projection 107 on rod 103 normally tends to hold said rod in its lowered position. A pipe 108 having therein a downwardly opening valve 109 extends from the upper portion of chamber 100 to the lower portion of chamber 101 thereby permitting oil to flow freely from said chamber 100 to chamber 101 below piston 102 when the same is raised, but preventing return flow of oil when the piston is caused to descend. A similar pipe 110 is provided with an upwardly opening valve 111 and a hand-operative choke valve 112. The pipes and chambers of the cylinder are full of oil. As the cam 51 (or cam 50 on shaft 42, which is provided with identically the same regulating means) rotates in the direction of the arrow, as indicated in Fig. 6, piston 102 will be raised against the force of spring 106 until said piston is seated within the contracted portion 100 of cylinder 99, the flow of oil through pipe 108 permitting this. When cam 51 has been brought to its upper or active position the point of connection 104 of rod 103 will have passed beyond the rotative center on shaft 43 of cam 51, as indicated in dotted lines in Fig. 6. Action of spring 106 therefore will tend to cause cam 51 to be rotated through rod 103. But oil is trapped beneath piston 102 and can only flow upward above the same through pipe 110 as fast as permitted by the extent of closure of choke valve 112 which may be varied as desired. Descent of piston 102 will therefore be retarded at first but after the upper edge thereof passes into enlarged chamber 101 the piston 102 may descend freely which it will do, thereby rotating cam 51 or similarly conditioned cam 50 and permitting spring 37 to cause arm 34 to close valve 28 or valve 29. By regulating the rate of flow of oil through pipe 110 by means of choke valve 112 the point at which this cut-off will take place relative to the upward stroke can be adjusted with the utmost accuracy and can be made to take place at any point of said upward stroke, as desired, thus regulating the amount of charging mixture drawn into the cylinder to the conditions of work being performed.

In the type of engine disclosed in which return of the parts is effected by gravity and owing to differences in the pumping action or degree of compression of the gases within the charged cylinder or from other causes, the point at which the weight-operating member and the engine piston stops may vary materially. For producing the most effective results it is necessary to provide an

ignition which will take place at the moment when the downward stroke ceases and at no other time. A very simple device for effecting this result is shown in Fig. 1 in which a weighted arm 113 is shown, pivoted at 114 to a projection 115 from cross bar 20, said weighted arm being held in almost balanced relation by means of a spring 116 adjustably connected by means of thumbscrew 117 to a lug 118 on said cross bar. Arm 113 is in the electric circuit of the ignition, as is an arm 119 secured to cross bar 20 and having an extended portion 120 underlying the end 121 of arm 113. When the weight- 5 operating member 20 and parts connected therewith come to rest at the end of the down stroke the inertia of weight 122 on arm 113 will be sufficient to overcome the force of spring 116 and cause end 121 to 10 contact with extension 120 thereby completing the ignition circuit and causing an igniting spark.

The operation of my device has been very fully given in connection with the detailed 15 description thereof. In general, supposing the parts to be as shown in Fig. 1 in which an explosion has taken place in cylinder 14 and the end of the upward stroke just reached, exhaust valve 30 of cylinder 13 having been closed and intake valve 28 20 opened at the moment of explosion in cylinder 14, said valve 28 having been closed before the completion of the stroke by rotation of cams 51 through action of cut-off 25 device, all as indicated diagrammatically in Fig. 4,—at the beginning of downward reciprocation the pressure generated by pumping piston 24 will actuate piston 78 and connecting rods 79 and 82 to rotate all of the 30 cams a quarter turn in the direction of the arrows with the result that cam 46 will come up, opening exhaust valve 31, and each of the other cams will be moved a quarter of a turn. In the meantime the charge in cylinder 13 will have been compressed. 35 When downward movement ceases, the sparking device will operate to ignite the charge in cylinder 13 and at the moment of ignition, through piston 58 in cylinder 56 40 and connecting rods 59, 65 and 73, shafts 42 and 43 will again be rotated a quarter of a turn, resulting in the closing of exhaust valve 46 and opening of intake valve 29, which in turn will be closed by the cut-off 45 mechanism at the proper point in the upward stroke. The beginning of downward movement, through the means already described, will now rotate all of the cams another quarter turn with the result that valve 50 50 55 60 65 30 will be opened. Explosion of the compressed charge in cylinder 14 will actuate the operating mechanism to rotate the cams another quarter turn closing valve 30 and opening valve 28, which will be cut off at the proper point in the upstroke, thus clos-

ing the cycle of operations and restoring the parts to the position indicated in Figs. 1 and 4.

I claim:

1. A power pumping apparatus embodying a motive fluid actuated motor piston, and admission and exhaust valves for the actuating fluid, a pump for delivering fluid under pressure embodying a pump piston connected with the motor piston and means 70 operated by the fluid pressure created by the pump piston for opening the exhaust valve of the motor.

2. A power pumping apparatus embodying successively acting motive fluid actuated 80 pistons, and admission and exhaust valves for the actuating fluid for each piston, a pump for delivering fluid under pressure embodying a pump piston connected with the motor pistons, means operated by the 85 fluid pressure created by the pump piston for opening the exhaust valves of the motor pistons and means operated by the actuating pressure for one motor piston for closing the exhaust valve for the motive fluid of the 90 other motor piston.

3. A power pumping apparatus embodying successively acting motive fluid actuated motor pistons, and admission and exhaust valves for the actuating fluid of each piston, 95 a pump for delivering fluid under pressure embodying a pump piston connected with the motor pistons to deliver fluid during the exhaust strokes of the motor pistons and means operated by the fluid pressure created 10 by the pump piston for opening the exhaust valves of the motor pistons alternately, one during each delivery stroke of the pump piston.

4. A power pumping apparatus embodying successively acting motive fluid actuated motor pistons, and admission and exhaust valves for the actuating fluid of each piston, a pump for delivering fluid under pressure 11 embodying a pump piston connected with the motor pistons to deliver fluid during the exhaust strokes of the motor pistons, means operated by the fluid pressure created by the pump piston for opening the exhaust valves of the motor pistons 1 alternately, one during each delivery stroke of the pump piston and means operated by the motive fluid pressure of each motor piston for closing the exhaust valve for the 12 motive fluid of the other motor piston. 1

5. A power pumping apparatus embodying successively acting motive fluid actuated motor pistons, and admission and exhaust valves for the actuating fluid of each piston, a pump for delivering fluid under pressure 1 embodying a pump piston connected with the motor pistons to deliver fluid during the exhaust strokes of the motor pistons, means operated by the fluid pressure created by the pump piston for opening the exhaust 1

valves of the motor pistons alternately, one during each delivery stroke of the pump piston and means operated by the motive fluid pressure of each motor piston for opening 5 the admission valve for motive fluid of the other motor piston.

6. A power pumping apparatus embodying successively acting motive fluid actuated motor pistons, and admission and exhaust valves for the actuating fluid of each piston, a pump for delivering fluid under pressure embodying a pump piston connected with the motor pistons to deliver fluid during the exhaust strokes of the motor 10 pistons, means operated by the fluid pressure created by the pump piston for opening the exhaust valves of the motor pistons alternately, one during each delivery stroke of the pump piston and means operated by 15 the motive fluid pressure of each cylinder for closing the exhaust valve and opening the admission valve for the motive fluid of the other motor piston.

7. An engine, a pump having the piston 25 thereof in actuating connection with the piston of the engine, an exhaust valve, and means rendered operative through compression of the fluid subject to the action of the pump and through expansion of the engine-operating fluid to open and close said exhaust valve successively and continuously at the proper moment in the cycle of operation of the engine.

8. An engine, a pump having the piston 35 thereof in actuating connection with the piston of the engine, an intake valve, and means rendered operative through compression of the fluid subject to the action of the pump and through expansion of the engine-operating fluid to open and close said intake valve successively and continuously at the proper moment in the cycle of operation of the engine.

9. An explosive engine comprising a plurality of engine units, a pump having the piston thereof in actuating connection with the pistons of said engine units, an exhaust valve for each engine unit, and means rendered operative by compression of the fluid 45 subject to the action of the pump and by expansion of the engine-operating fluid to operate said valves successively.

10. An explosive engine comprising a plurality of engine units, a pump having the piston thereof in actuating connection with the pistons of said engine units, an exhaust valve and an intake valve for each engine unit, and means rendered operative by compression of the fluid subject to the 55 action of the pump and by expansion of the engine-operating fluid to operate the exhaust valve and then the intake valve of one engine unit, and the exhaust valve and intake valve of another engine unit in successively timed relation.

11. An explosive engine comprising a plurality of engine units each connected to and adapted to operate a common member, and said common member, an exhaust valve and an intake valve on each engine unit, a 70 cam shaft and cams for operating each set of valves on each engine unit, and means to rotate both cam shafts simultaneously a quarter turn in the same direction at each explosion and compression stroke of the engine. 75

12. An explosive engine, a pump having the piston thereof in actuating connection with the piston of the engine, an exhaust valve and an intake valve for said engine, a 80 cam shaft and cams thereon for operating said valves, means to rotate said shaft actuated by explosion in the engine cylinder, and other means to rotate said shaft operated by fluid compression in the pump. 85

13. An explosive engine, a pump having the piston thereof in actuating connection with the piston of the engine, an exhaust valve and an intake valve for said engine, a cam shaft and cams thereon for operating 90 said valves, a cylinder provided with an open passageway connecting said cylinder with the cylinder of the pump, a piston in said cylinder and connections therefrom to said shaft to rotate the same when fluid compression in the pump operates said piston. 95

14. An explosive engine, a pump having the piston thereof in actuating connection with the piston of the engine, an exhaust valve and an intake valve for said engine, a 100 cam shaft and cams thereon for operating said valves, a cylinder provided with an open passageway connecting said cylinder with the cylinder of the engine, a piston in said cylinder and connections therefrom to said shaft to rotate the same when an explosion takes place and the expanding gases of combustion operate said piston. 105

15. An explosive engine, a pump having the piston thereof in actuating connection 110 with the piston of the engine, an exhaust valve and an intake valve for said engine, a cam shaft and cams thereon for operating said valves, a cylinder provided with an open passageway connecting said cylinder 115 with the cylinder of the pump, a piston in said cylinder and connections therefrom to said shaft to rotate the same when fluid compression in the pump operates said piston, another cylinder provided with an open passageway connecting said cylinder with the cylinder of the engine, a piston in said last named cylinder and connections therefrom to rotate said shaft in alternation with rotation from said pump-connected cylinder 120 when an explosion takes place and the expanding gases of combustion operate said last named piston. 125

16. An explosive engine, a pump having the piston thereof in actuating connection 130

- with the piston of the engine, an exhaust valve and an intake valve for said engine, separate valve gear including a spring-actuated lever for operating each of said valves, 5 a cam shaft having cams in actuating engagement with said levers, and means to effect intermittent rotation of said shaft by explosion in the engine cylinder and fluid compression in the pump.
- 10 17. An explosive engine, a pump having the piston thereof in actuating connection with the piston of the engine, an exhaust valve and an intake valve for said engine, separate valve gear including a spring-actuated lever for operating each of said valves, 15 a cam shaft having cams in actuating engagement with said levers, ratchet wheels on said shaft, pawls for said ratchets, a cylinder and a piston therein operable by explosion of the engine, said piston having actuating connection with one of said pawls, and another cylinder and piston therein operable by fluid compression within the pump having actuating connection with the other 20 of said pawls, whereby said shaft is intermittently rotated at each explosion and each compression stroke of the engine.
18. An explosive engine, a pump having the piston thereof in actuating connection 30 with the piston of the engine, an exhaust valve and an intake valve for said engine, separate valve gear including a spring-actuated lever for operating each of said valves, a cam shaft having cams in actuating engagement with said levers, four-toothed ratchet wheels on said shaft, pawls for said ratchets, a cylinder and a piston therein operable by explosion of the engine, said piston having actuating connection with one of said pawls, 35 and another cylinder and piston therein operable by fluid compression within the pump having actuating connection with the other of said pawls, whereby said shaft is intermittently rotated a quarter-revolution at each explosion and each compression stroke 40 of the engine.
- 45 19. An explosive engine comprising a plurality of engine units each connected to and adapted to operate a common member, and 50 said common member, an exhaust valve and an intake valve on each engine unit, a cam shaft and cams for operating each set of valves on each engine unit, supplemental cylinders provided with open passageways connecting said cylinders with the cylinders of the different engine units, respectively, a piston working in each of said supplemental cylinders, and connections between said pistons and to the cam shafts, whereby an explosion in any engine unit will rotate all 55 said cam shafts simultaneously.
- 60 20. An explosive engine comprising a plurality of engine units each connected to and adapted to operate a common member, and 65 said common member, an exhaust valve and
- an intake valve on each engine unit, a cam shaft and cams for operating each set of valves on each engine unit, supplemental cylinders provided with open passageways connecting said cylinders with the cylinders of the different engine units, respectively, a piston working in each of said supplemental cylinders, a single rod connected to both of said pistons, a ratchet fast on each cam shaft, a swinging pawl operating therewith, and 70 links pivotally connecting said rod and said swinging pawls.
- 75 21. An explosive engine comprising a plurality of engine units each connected to and adapted to operate a common member, and 80 said common member, an intake valve for each engine unit, means operated by explosion in any one of the engines for positively opening the intake valve of another engine at the beginning of outward movement of the engine pistons, and means for effecting closure of the opened valve at a predetermined point in the engine stroke.
- 85 22. An explosive engine comprising a cylinder, piston, and inlet valve with means for 90 opening the inlet valve during the initial outward movement of the piston and means controlling the closing of said valve embodying a fluid containing dash pot and means for regulating its speed of operation where- 95 by the valve may be closed at the desired point in the outward stroke of the piston.
- 100 23. An explosive engine comprising an inlet valve, a shaft, a cam thereon movable between fixed limits independently of said shaft, means to rotate the shaft and thereby move the cam into active position positively to open the valve, an oil-filled receptacle comprising a cylindrical chamber, a piston in said chamber, a rod connecting said piston 105 and said cam, by which actuation of said cam will elevate the piston, means actuating said rod to withdraw said cam from its active position, and means for momentarily trapping oil beneath said piston for retard- 110 ing said withdrawing action.
- 115 24. An explosive engine comprising an inlet valve, a shaft, a cam thereon movable between fixed limits independently of said shaft, means to rotate the shaft and thereby move the cam into active position positively to open the valve, an oil-filled receptacle comprising a cylindrical chamber, a piston in said chamber, a rod connecting said piston 120 and said cam, by which actuation of said cam will elevate the piston, means actuating said rod to withdraw said cam from its active position, a pair of pipes connecting the upper and lower portions of said chamber having valves to permit flow of oil through 125 said pipes in opposite directions only, and a choke valve in one of said valves to regulate flow of oil therethrough and retard downward movement of said piston.
- 130 25. An explosive engine comprising an in-

let valve, a shaft, a cam thereon movable between fixed limits independently of said shaft, means to rotate the shaft and thereby move the cam into active position positively 5 to open the valve, an oil-filled receptacle comprising a cylindrical chamber, said chamber being provided with a contracted upper portion, a piston working in said contracted portion, a rod connecting said piston 10 and said cam by which actuation of said cam will raise the piston, means actuating said rod to withdraw said cam from its active position, means permitting oil to flow freely from said contracted portion to the lower 15 portion of said cylinder, and regulable means for restricting return flow, whereby the piston will be retarded in its return movement to a predetermined extent.

26. An explosive engine comprising a vertically mounted cylinder, a weight connected 20 to and lifted by the piston of said engine, and an ignition system comprising a fixed contact and a pivoted contact, said pivoted contact being provided with a weight and being spring held in non-contacting relation 25 with said fixed contact, inertia of said pivoted contact operating to bring the same into contacting relation at the termination of the return stroke.

In testimony whereof I affix my signature 30 in presence of two witnesses.

KENNEDY DOUGAN.
